HIGH TENSION SWITCH

Karl Felten, Siegburg, Germany

Application May 9, 1928, Serial No. 276,321, and
in Germany May 16, 1927

1 Claim. (Cl. 177—311)

In the use of the high tension switches hitherto known having oil submerged contacts and irrespective of whether the switch is provided with horizontally guided contact bridges or with contact discs rotatably arranged on a switch shaft it is not possible during the working to obtain a knowledge of the condition of the contact faces. A knowledge of the condition of the contact faces can be obtained only during an investigation of the switch on cutting off the current. However it frequently occurs that the contact faces become defective during the actual working and since these defects cannot be observed in the switches while in use, such defects not infrequently result in extremely dangerous switch explosions. These explosions occur most frequently during the switching in and out of the contacts because in most of the devices hitherto employed the switching in and out takes place slowly, accompanied therefore by intense sparking.

The present invention has for its object to remove the drawbacks above mentioned. To this end according to this invention during the switching in of the main contacts, by means of special secondary contacts, a resistance arranged in parallel with the main contacts is switched in simultaneously, the arrangement being such that, in the event of any damage occurring to the main contact faces, the resistance referred to is traversed by the current, thus creating a magnetic field which during the working at once causes an appropriate signaling device to become operative. In this way therefore a knowledge of the condition of the contact faces is indicated during the working so that the causes of any possible switch explosion may be removed at the very outset. By preference contact discs or levers are employed and arranged so that they can be cut in or cut out during their fastest part of the movements, thereby preventing extreme sparking during the switching actions and consequently excluding the possibility of a switch explosion.

The invention is illustrated by way of example in the accompanying drawing in one form.

Fig. 1 is a diagrammatical representation thereof in section on the line 1—1 of Figure 2.

Fig. 2 is a similar section on the line 2—2 of Figure 1.

Fig. 3 is a broken away perspective view illustrating the relative angular positions of the movable contact members of the switch.

The gear shafts *a* and *b* are driven manually or from any convenient driving motor, and in

turn drive the switch shaft *c* of the oil-charged high tension switch *z*. This shaft *c* carries three discs *d*, *e* and *f* made of insulating material and provided on part of their circumference with contact faces *d'*, *e'*, *f'* respectively. In the 60 switched-in position illustrated in the drawing the central switch disc *e* connects the main contacts *g*, *h* of the terminals *i*, *k* of the switch conductively one with the other. The current therefore flows from the terminal *i* through the 65 contact disc *e* direct to the terminal *k*. The contact faces *d'*, *f'* of the two other discs *d*, *f* are in practice shorter than the contact face *e'* of the disc *e* and serve solely to connect the discs *d* and *f* to the secondary contacts *l*, *m* of the 70 terminals *i*, *k*. The contact faces *d'*, *f'* are connected one to the other by a resistance *n*. As soon therefore, during the working, as the main contact faces *g* or *h* become defective the current flows through the terminal *i*, not through the 75 switch disc *e*, but over the switch disc *f* and through the resistance *n*, which as will be seen lies in the circuit parallel with the switch disc *e* and over the switch disc *d* to the terminal *k*. The resistance *n* which is wound about the switch 80 shaft *c* and acts as a solenoid creates a magnetic field in the closed magnetic circuit *o* thereby energizing the coil *p* included in said magnetic field. By connecting the coil *p* to a suitable indicating device such for instance as a bell *B*, 85 Fig. 3, it is thus possible at any time during the working at once to indicate injury to the contact faces *g*, *h*. If the main contact faces *g*, *h* are quite intact the current flows obviously, not through the resistance *n*, but directly over the 90 contact disc *e*, whereby the indicating device connected to the coil *p* remains unactuated. From the foregoing, it will be seen that the auxiliary circuit, which includes the contact members *d'* and *f'*, constitutes an inductive impedance to 95 the flow of current through said auxiliary circuit.

The three discs *d*, *e* and *f* are preferably arranged so that on switching in first of all the discs *d* and *f* are brought into contact with the 100 secondary contacts *l*, *m* before the main contacts *g* and *h* are closed by the switch disc *e*. This is accomplished by disposing the contact members *d'* and *f'* on their respective discs so that they are in staggered relation to each other 105 and to the contact member *e'*, the disc *e* of which is disposed between the discs *d* and *f*, as clearly shown in Fig. 3. By reason of this disposition the contact members *d'*, *f'* will close the circuit through the contact members *l* and *m* 110

in advance of the closing of the circuit through contacts *d* and *e* by the contact member *e'*, and will remain closed for a short period after the main circuit through *g*, *h* has been opened. 5 Since the contact members *d'* and *f'* each serve to connect with only one terminal or fixed contact member, they can be of considerably shorter length than contact member *e'*, which alone serves to close the gap between the terminals 10 *g* and *h*. The current therefore must first of all flow for a short time through the resistance *n* before the contact faces *g* and *h* are closed by the contact disc *e*. The closing of the auxiliary circuit through the contact members *d'* and *f'* 15 before the main circuit is closed, and maintaining said auxiliary circuit closed after the main circuit is opened, introduces an impedance which is not only effective to reduce arcing, but causes the switching in of the main circuit to occur at 20 the highest speed of the discs. In other words, the contact members *d'*, *e'* and *f'* are of such length and so disposed that after contact has been made they remain in contact during continued rotation of the discs about a predetermined angle, as clearly indicated in Fig. 1. 25 This extension of the contact surfaces beyond the distance necessary to make contact between the two terminals, makes possible an over-switching so that the switch does not have to be instantaneously stopped at the moment of contact and greater switching speeds are obtainable be-

cause of the possibility of gradual retardation. The same is, of course, true of the opening of the switch.

In the constructional form shown the switch has only one interrupting point between the two poles *i*, *k*. By increasing the number of switch discs the number of interrupting points could, however, be likewise increased.

What I claim is:—

A high-tension switching device, comprising in combination, a pair of fixed terminals each having a main contact and an auxiliary contact, a shaft mounted for rotation between said terminals, an insulating disc secured on said shaft and having a contact element in position to engage both of said main contacts thereby to form a main circuit through said terminals, a pair of insulating disks secured in spaced relation on said shaft and each having a contact element in position to engage one of said auxiliary contacts, a low impedance element connecting the contact elements of said pair of disks thereby to form a shunt circuit through said terminals, said contact elements being relatively so disposed that upon rotation of the shaft the shunt circuit will be closed before the main circuit and will be opened after the opening of the main circuit, said device also including means to indicate when current flows in said impedance element.
